UNITED STATES PATENT OFFICE.

DUANE H. CHURCH, OF WALTHAM, MASSACHUSETTS, ASSIGNOR TO THE AMERICAN WATCH COMPANY, OF SAME PLACE.

STEM WINDING AND SETTING WATCH.

SPECIFICATION forming part of Letters Patent No. 295,484, dated March 18, 1884.

Application filed August 23, 1883. (No model.)

To all whom it may concern:

Be it known that I, DUANE H. CHURCH, of Waltham, in the county of Middlesex and State of Massachusetts, have invented certain Improvements in Pendant Winding and Setting Watches, of which the following is a specification.

This invention has for its object to provide improved means for making the hand-setting train of a pendant winding and setting watch operative and inoperative by the movement of the yoke which is pivoted upon the center of the crown-wheel, whereby motion is imparted from the stem either to the setting or winding wheels.

The invention consists in adapting the intermediate setting-wheel to move in and out in a direction at right angles to its plane of rotation, instead of moving with the yoke parallel with said plane, and in the provision of means whereby said intermediate wheel is normally held with a yielding pressure against the yoke and in engagement with the minute-wheel of the hand-setting train when the yoke is in position for hand-setting, and is forced inwardly out of engagement with said wheel by the movement of the yoke to position for winding, as I will now proceed to describe.

Of the accompanying drawings, forming a part of this specification, Figure 1 represents a side view of a portion of a watch-plate provided with my improvement, the yoke being in position for setting. Fig. 2 represents a section on line $x-x$, Fig. 1. Fig. 3 represents a view similar to Fig. 1, showing the yoke in position for winding. Fig. 4 represents a section on line $y-y$, Fig. 3. Fig. 5 represents a view of the opposite side of the plate. Fig. 6 represents a side view of a portion of the plate, showing a lever projecting through the case as a means for shifting the yoke.

The same letters of reference indicate the same parts in all the figures.

In the drawings, a represents a portion of the plate of a watch, and b a portion of the case having the pendant c .

d represents the winding-arbor or pipe-key, adapted to rotate in the pendant c , and provided with the usual bevel-pinion, e , which meshes with the crown-wheel f , on which the yoke g is pivoted. Said yoke is adapted to

oscillate, as usual, on the wheel f , and carries at one end the usual intermediate winding-wheel, h , which is always in engagement with the wheel f , and is moved by the yoke into and out of engagement with the mainspring winding-wheel.

i and j represent, respectively, the cannon-pinion and minute-wheel of the hand-setting train, said wheels being journaled on arbors affixed to the watch-plate.

The construction thus far described is the common one, and forms no part of my invention.

k represents the intermediate wheel through which motion is communicated from the crown-wheel f to the minute-wheel j .

In carrying out my invention, I provide the plate a with a cavity, l , under said intermediate wheel, and with a fixed arbor, m , projecting from said cavity. The intermediate wheel, k , rotates on said arbor, and is adapted to slide thereon at right angles to its plane of rotation. The cavity l is of sufficient depth to permit the intermediate wheel, k , to sink below the plane of the minute-wheel, as shown in Fig. 4, and thus become disconnected therefrom by a movement at right angles to the plane of rotation of said wheels. The intermediate wheel, k , is held with a yielding pressure against the yoke, and is normally raised from the bottom of the cavity l into the plane of the minute-wheel j by a spring, m' , as shown in Fig. 2.

The outer side of the intermediate wheel, k , is provided with a conical projection, n , and the yoke is provided with a corresponding recess or orifice, o , which coincides with the projection n and permits the intermediate wheel, k , to be forced outwardly by the spring only when the yoke is in position for setting, as shown in Figs. 1 and 2. When the yoke is moved to position for winding, as shown in Fig. 3, the orifice o is moved away from the projection n , and the inner surface of the yoke bearing against said projection forces the intermediate wheel into the cavity l and disengages it from the minute-wheel j , as shown in Fig. 4. It will be seen that by adapting the yoke to move the intermediate wheel, k , at right angles to the plane of its rotation in separating it from the minute-wheel, there is no tendency to rotate the minute-wheel, and thus move the hands by the separation of said wheels. When the intermediate wheel is supported by the yoke,

and moved thereby in a direction parallel to or in line with the plane of its rotation, as usual, it is liable to partially rotate the minute-wheel in being separated from it, thus necessitating the readjustment of the hands. The yoke may be shifted from one position to the other by an endwise movement of the winding-arbor, or, if said arbor is not movable endwise, by means of a lever, *s*, pivoted to the case and having one arm bearing against a projection, *s'*, on the yoke, and another arm, *s''*, projecting through the margin of the case, as shown in Fig. 6. When the arm *s''* is pulled outwardly, the arm *s'* pushes the yoke from the winding to the setting position, and when the arm *s''* is pushed inwardly a spring, *t*, forces the yoke into winding position.

I am aware that it is not new to make the intermediate wheel, *k*, movable in a direction at right angles with the plane of its rotation for the purpose of engaging it with and disengaging it from the minute-wheel without displacing the latter; hence I do not claim this feature.

25 I claim—

1. In a pendant winding and setting watch, the combination, with the hand-setting wheels *i* *j* and crown-wheel *f*, rotated by the winding-arbor, of the intermediate winding-wheel adapted to move on a fixed stud or arbor in a direction at right angles with the plane of its rotation, into and out of engagement with its co-operating wheels, a spring adapted to move

the intermediate wheel outwardly into engagement with said co-operating wheels, and the yoke bearing upon the intermediate wheel and adapted to control the position thereof, as set forth.

2. In a pendant winding and setting watch, the combination, with the hand-setting wheels *i* *j* and the crown-wheel *f*, rotated by the key-pipe, of the intermediate hand-setting wheel, *k*, adapted to move on its supporting pin or arbor in a direction at right angles with the plane of its rotation, the winding-wheel carrying yoke *g*, pivoted on the crown-wheel, and a spring which presses the hand-setting wheel *k* outwardly against the yoke, said yoke and wheel being provided, respectively, with an orifice and a projection, whereby when the yoke is in its hand-setting position the spring is allowed to force the wheel *k* outwardly into engagement with the crown-wheel and minute-wheel, and when the yoke is in its winding position the wheel *k* is forced inwardly out of engagement with said crown and minute wheels, as set forth.

In testimony whereof I have signed my name to this specification, in the presence of two subscribing witnesses, this 16th day of August, 1883.

DUANE H. CHURCH.
